APPARATUS FOR MAKING METALLIC SURFACING SHEETS

Dwight A. Johnston, Youngstown, Ohio, assignor to McKay Machine Company, Youngstown, Ohio, a corporation of Ohio

Application September 14, 1939, Serial No. 294,902

5 Claims. (Cl. 153—77)

This invention relates to a method and apparatus for forming metallic surfacing sheets and more particularly to an improved method and apparatus for embossing the sheet stock with the required channels or corrugations in a very accurate and economical manner.

The metallic sheet stock normally used in the manufacture of surfacing units for roof and wall use is of relatively thin gauge and as such has little resistance to twisting or torsional deformation and it has therefore been found desirable to provide the sheets with corrugations or channels for the primary purpose of strengthening the individual units. In practice, such corrugation is usually placed longitudinally of the sheets in laterally spaced relation along each side edge of the sheets and in certain products a longitudinal corrugation is also positioned centrally of the sheets.

Aside from the strengthening utility of the corrugations along the side edges of the sheets, consideration has also been given to the use of the corrugations as a seal to prevent the lateral passage of water by capillary movement or otherwise between the laterally overlapped side edges of the respective sheets onto the base surface below the metal sheets. This is accomplished by so designing the transverse contour of the side corrugations that the corrugation or channel along the side of one sheet will nest into the corrugation or channel along the adjacent side of an overlapped sheet in such manner that a tight joint is provided and a protected trough extending longitudinally of the seam is formed to carry any water which may have gotten between the overlapped sheets down to the gutter of the building.

To strengthen the sheets along their transverse directions and to provide means to prevent water from passing upwardly between longitudinally overlapped sheets by capillary attraction and otherwise, it is now proposed to incorporate in each sheet a transverse corrugation adjacent the lower edge of the sheet and extending the full distance between the corrugations which extend longitudinally along the side edges of the sheet.

Inasmuch as the longitudinal corrugations may be embossed in the sheets by continuous or semi-continuous rolling processes, such corrugating may be easily and economically accomplished. However, the imposition of the transverse corrugations which interconnect the longitudinal corrugations presents considerable difficulty, particularly when it is desired to complete the man-

ufacture of the surfacing units by an economical continuous process, since the interval between the end of the sheet and the transverse corrugation must be accurately maintained to insure the accurate interfitting of the units when laid upon the wall or roof and since the extent of and variation in the length of the sheets normally prevents the use of a conventional die rolling stand.

It is accordingly the primary object of the invention to provide an improved apparatus for forming transverse corrugations adjacent one end of metallic sheets previously corrugated longitudinally whereby the units may be manufactured with precise accuracy and with economy.

A more specific object of the invention is the provision of an improved apparatus for forming transverse corrugations adjacent one end of metallic sheets previously corrugated longitudinally, which corrugations extend the entire distance between the longitudinal corrugations, and which is accomplished without injury to the adjacent end of the sheets while the transverse corrugations are accurately positioned with respect to the adjacent end of the sheets and the longitudinal corrugations. This is accomplished, in accordance with the present invention, by providing a pair of mandrels, one positioned below the path of travel of the sheets and the other positioned thereabove, each provided with roll rings freely rotatable thereon and arranged in sets to provide a rigid guiding and retaining pass which is continuously effective during the entire traverse of the sheets and during the transverse corrugating operation which takes place while the sheets are so retained and guided. The means employed to corrugate the sheets transversely consists of the die segments or rolls carried by the mandrels between the ring sets and rotatable from an inoperative position through an arc including the plane of the axes of the mandrels to effect the embossing or corrugating operation during the travel of the stock sheets through the pass.

Yet another object of the invention is the provision in a continuous production process of improved means for initiating rotative movement of a set of die rolls whose function is to emboss or corrugate sheet material coming therebetween and for applying sufficient power for the rotation of said rolls to insure the performance of the embossing or corrugating operation without damage to the material being worked on.

A still further object of the invention is the provision in an apparatus of the kind mentioned immediately above of an improved arrangement

for the synchronization of the rotative speed of the dies and the speed of travel of the stock through the pass whereby the desired deformation of the stock being worked on may be accomplished without marring the surface of the stock.

These and other objects and advantages of the invention will become apparent from a consideration of the following detailed specification and the accompanying drawings wherein there is specifically disclosed a preferred embodiment of the invention.

In the drawings:

Figure 1 is a side view of an apparatus constructed in accordance with the principles of the invention and capable of carrying out the method disclosed herein.

Figure 2 is a transverse sectional view of the apparatus of Figure 1 taken along the line II—II of Figure 1;

Figure 3 is an enlarged side view of a portion of the apparatus of Figure 1 with certain outboard housings removed; and

Figure 4 is a sectional view through the transverse corrugating rolls and guides mounted thereon.

The apparatus of the invention consists generally of a series of stands of forming rolls, indicated generally by the reference numeral 10, mounted on the base 11, a cross-corrugating roll stand 12 and a pull out roll stand 13 also mounted on the base 11. In accordance with usual practice, the stands 10, which may vary in number from a relatively few to 12 or more depending on the product being produced, are each provided with an upper and lower forming roll having complementary interengaging annular dies of progressively increasing depth whereby the metal sheet material is provided with longitudinally extending deformations or corrugations as the sheets pass through the forming mill constituted by the stands. A bottom supporting roll 14 and side guiding rolls 15 are provided to guide the sheets into the first stand of the mill.

During operation of the mill constituted by the series of roll stands, as explained above, which mill may be of conventional construction, the sheets as they issue from the mill are provided with the longitudinal deformations or corrugations as aforesaid and it is within the province of this invention to provide the sheets with accurately positioned transverse deformations or corrugations as the sheets issue from the primary forming mill without interfering with the speed of travel of the sheets or the operation of the mill. For the accomplishment of this object, upper and lower rolls 16 and 17, respectively, are mounted for rotational movement about parallel axes lying in a plane normal to the direction of movement of the sheets as they issue from the mill. Rolls 16 and 17 are journaled in inboard and outboard housings 18 and 19, respectively, and one of the rolls, as 16, is provided with a die segment 20 and the other of the rolls, as 17, is provided with a die segment 21, the two die segments being complementary to each other.

In the apparatus specifically disclosed, the rolls of the forming mill are each provided with annular dies adjacent their ends and also centrally thereof whereby the sheets passing through the mill will be provided with longitudinally extending deformations extending along either side edge of each sheet and with the longitudinally extending rib along the center of the sheet. As stated above, the transverse corrugations in the sheets extend substantially the entire interval between

the longitudinal corrugations and therefore the rolls 16 and 17, as specifically disclosed, are each provided with two segmental die portions spaced along the axes of each roll, the space intervening therebetween forming the pass for the said central rib.

Rolls 16 and 17 are keyed to upper and lower shafts 22 and 23, respectively, which in turn are journaled in bearing blocks 24 mounted in the housings 18 and 19. The pressure exerted between said rolls may be controlled in accordance with usual practice by rotation of the hold-down screws 25. Shafts 22 and 23 are geared together by the spur gears 26 keyed to the shafts and intermeshing with each other, as indicated in the drawings. Rolls 16 and 17 are each provided with annular recesses 27 at their ends and annular grooves 28 in their mid-sections. Fitting within the recesses 27 of the upper roll 16 are the annular rings 30 having peripheral die surfaces corresponding to the contours of the upper surfaces of the side corrugations formed in the sheets by the roll stands 10. Rotatably mounted in the annular recesses 27 in the lower roll 17 are the annular rings 31 having peripheral die surfaces complementary to the outer surfaces of the rings 30 and conforming to the contour of the lower surface of the side corrugations rolled into sheets by the stands 10. Likewise, annular rings 33 and 34, having complementary peripheral die surfaces forming a pass to guide the central rib formed in the sheets, are mounted in the annular grooves 28 provided in the upper and lower rolls 16 and 17, respectively. The rings 30, 31, 33 and 34 are each freely rotatable in their respective recesses and with respect to the rolls with which they are associated, suitable bushings 36 and 37 being provided to reduce the friction between the rings and the rolls.

Rolls 16 and 17 are so keyed together by the gears 26 that the complementary dies carried thereby will be in their proper operative relative positions as the dies move through the plane of the axes of rotation of the rolls as the rolls are rotated. Extending outwardly from the face of the upper roll 16 and substantially co-extensive with the die 20 is the key 39 rigidly carried by and movable with the upper roll 16. The key 39 is positioned adjacent a circumferential end of the die segment 20 and its function is to provide an abutment for engagement by the leading ends of the sheets, thereby providing means for the initial rotation of the rolls as the sheets enter the transverse deforming pass. As shown in Figure 3, the interval between the key 39 and the adjacent circumferential ends of the dies 20 and 21 is such that when the rolls are in their initial starting positions the projections of the dies 20 and 21 will lie just outwardly of the path of travel of the sheets through the pass.

Keyed to the lower shaft 23 is a sprocket 40 about which is entrained a chain 41 connected at one end with the piston of an air cylinder 42 and at its other end with a spring 43. The arrangement of the parts is such that actuation of the cylinder 42 rotates the rolls 16 and 17 in such direction from their initial starting position that the die segments 20 and 21 will be caused to move beyond the plane of the axes of rotation of said rolls along with the sheet stock passing therebetween to effect the transverse deformation in the sheet stock. The spring 43 returns the rolls to their initial starting positions upon the withdrawal of air pressure to the cylinder 42.

Die segment 21 on roll 17 is provided with an

end shoulder 45 adapted to engage a fixed abutment 46 to limit the return rotational movement of the shafts and rolls. The various parts so relatively positioned that when the abutment 46 is engaged by the shoulder 45, the key 39 is positioned immediately beyond the plane of the axes of the roll shafts 22 and 23. The circumferential interval between the key 39 and the dies 20 and 21 is predetermined in accordance with the dimension requirements of the product being manufactured and the arrangement insures the maintenance of the proper interval between the ends of the sheets and the transverse corrugation during the manufacture of the sheets.

Between the last pass of the forming mill and the pass formed by the rolls 16 and 17 are the upper and lower guide shoes 49 and 50, respectively, which are so shaped and spaced that the longitudinally corrugated sheets issuing from the forming mill will be accurately guided into the pass formed by the rolls 16 and 17 and the rings rotatably mounted on these rolls. Upper guide 49 is carried by a member 51 which in turn is adjustably attached to the base of the machine and the lower guide 50 is carried by a standard 52 mounted on the base 11. Lower guide 50 is forked or slotted to receive a roller or skid 54 normally biased to upper position in the path of travel of the sheets between the guides and operatively connected with the normally open switch 55. Switch 55 is conveniently supported on the standard 52.

Extending up through the abutment 46, which may also be an integral part of the standard 52, is the plunger 56 suitably guided in the standard 52 and biased to upper position by the spring 57. As indicated in Figure 3 of the drawings, the upper end of the plunger 56 is adapted to engage the shoulder 45 of the die segment 21. The lower end of the plunger 56 is operatively connected with the switch 58 and the arrangement is such that when the plunger is in its lower position, as shown in Figure 3 of the drawings, the switch 58 will be open but when the plunger is moved to its upper position by the spring 57 upon movement of the shoulder 45 away from the abutment 46 the switch 58 will be closed.

Air is supplied to the cylinder 42 from a suitable source through conduit 60, three way valve 61 and conduit 62 interconnecting the valve and the cylinder. Valve 61 is operated by solenoid 63, the energizing circuit for which includes a suitable current source 64 and the switches 55 and 58 in series. One way metering valve 66 is interposed in the conduit 62 to adjustably meter the flow of air into one end of the cylinder 42. Valve 66 places no restriction on the flow of the air outwardly from the said end of the cylinder 42. A similar oneway metering valve 67 connects the other end of the cylinder 42 with the atmosphere, the arrangement being such that an unrestricted outward flow of air may take place while the air coming into the said other end of the cylinder may be controllably metered.

Positioned outwardly of the cross-corrugating stand 12 is the pull-out stand 13 having a pair of driven pinch rolls 69 which are operative to engage the sheets as they issue from the cross-corrugating pass and to pull the sheets clear of the machine. Interposed between the cross-corrugating stand 12 and the pull-out stand 13 are straightening rolls 70 suitably and adjustably mounted by the adjacent housings or the base 11.

The operation of the apparatus described above is as follows:

During normal operation of the machines the rolls of the forming stands 10 and of the pull-out stand 13 are continuously driven at a constant rate of speed and as the successive sheets are fed into the machine past the guide rolls 14-15 the rolls of the stands will engage the sheets and roll in the longitudinal deformations, 10 as explained above. The sheets, on issuing from the last forming stand, will pass between the guides 49 and 50 and into the pass between shafts 22 and 23 of the cross-corrugating stand. As a sheet reaches the position of the roller 54 15 the roller will be depressed and switch 55 closed. The sheet on entering the pass aforesaid will engage the key 39 and impart initial rotational movement to the shafts 22 and 23. Initial movement of the lower shaft 23 will result in movement of the shoulder 45 of the die segment 21 20 away from the abutment 46 and the upper end of the plunger 56, allowing the plunger to move upwardly and the switch 58 to close. Switches 55 and 58 will now both be closed and the solenoid 63 energized. Energization of the solenoid actuates valve 61 to interconnect conduit 60 with conduit 62, thereby allowing air under pressure to flow to the upper end of cylinder 42, which results in downward movement of the piston in 25 the cylinder and movement of the chain 41. The die segments 20 and 21, being keyed to the shafts 22 and 23, will now be rotated into engagement with the sheet between the shafts to effect the transverse deformation in the sheet and will 30 move past the plane of the axes of the shaft to a position clear of the path of movement of the sheet. By adjustment of the valve 66 the speed of rotation of the die segments may be correlated with the speed of movement of the sheet, thereby insuring smooth operation of the process.

As the trailing end of the sheet aforesaid passes over the roller 54 the roller will be moved to upper position by its biasing means, thereby 45 opening the switch 55. The solenoid energizing circuit is thus opened and the valve 61 will be moved to opposite position closing conduit 63 and interconnecting conduit 62 with an outlet to the atmosphere 71. The air above the piston in cylinder 42 is now free to move out through conduit 62 and outlet 71 and the spring 43, connected with the other end of the chain 41 and previously tensioned by actuation of cylinder 42, will rotate the die segments 20 and 21 back toward their initial starting positions. To allow 50 a sufficient time interval for the end of the sheet to clear the pass between the shafts 22 and 23 before the dies 20 and 21 are moved back through the pass, valve 67 is employed to meter the flow of air into the lower end of the cylinder 42. By adjustment of the valve 67 the rate of return movement of the dies may be controlled.

It should now be apparent that I have provided an improved method and apparatus for carrying out the method which is capable of accomplishing the objects initially set out. The employment of the guide rings 39-34 on the rolls carrying the die segments 20 and 21 insures the accurate lateral alignment of the transverse corrugations and the employment of the key 39 insures the accurate longitudinal spacing of the corrugations. By employing positive power driving means for the segmental dies 20 and 21 during their working period the transverse corrugation 75 is effected without injury to the end of the

sheet and without undue marring of the surfaces of the sheet. Moreover, the transverse corrugating is accomplished without interfering with the movement of the sheets through the machine or the operation of the forming mill thereof and the machine and process is capable of operation at high productive speeds.

It should be understood that various modifications may be made in the machine, organization and structure without departing from the spirit or scope of the invention. For example, the shafts carrying the die segments may be driven by means other than that specifically disclosed and instead of returning the dies to their original position by reverse movement of the parts an arrangement may be utilized whereby the dies would move only in one direction. For example, the lower shaft 23 may be initially moved through 180° counter-clockwise, as viewed in Figure 3, to effect the transverse deformation and as the trailing end of a particular sheet clears the pass between the shafts 22 and 23 the shaft 23 may continue to counter-clockwise rotation through another 180° back to its original starting position, as shown in the figure. This may be accomplished by a suitably geared single revolution clutch or other equivalent means well known in the art and by employing suitably retractile limiting means to insure the accurate positioning of the parts at their initial starting positions.

It is also contemplated that instead of actuating the transverse deforming dies by an air cylinder in one direction and a spring in the other direction, as specifically illustrated and described, or employing a driving means therefor, as explained in the preceding paragraph, a double acting fluid pressure cylinder may be employed to rotate the dies in opposite directions and this may be accomplished by attaching one end of the chain 41 (Figures 1 and 3) to one end of the cylinder and the other end of the chain to the other end of the cylinder, whereby fluid pressure actuations of the cylinder in either direction will cause a corresponding movement of the dies. Or, instead of employing the double acting cylinder, as stated, a single acting cylinder may be employed in place of the spring 43 of the modification specifically shown and described. Thus, it should be understood that the specific means employed to actuate the dies 16, 17 is immaterial so far as the broader aspects of the invention are concerned.

What I claim is:

1. Apparatus for imparting transversely extending deformations in metal sheets having longitudinally extending deformations comprising in combination a pair of spaced parallel shafts,

freely rotating annular rings journaled on said shafts and arranged in pairs to provide guiding passes coincident with said longitudinal deformations, complementary deforming dies keyed to 5 said shafts intermediate said rings, and means to rotate said shafts in unison but in opposite directions whereby a metal sheet may be deformed transversely while passing longitudinally between said shafts and while being guided by said rings.

10 2. Apparatus for imparting transversely extending deformations in metal sheets having longitudinally extending deformations comprising in combination freely rotating annular rolls arranged in pairs and having complementary annular surfaces to closely fit said longitudinal deformations on opposite sides of said sheets, a pair of transversely extending carriers positioned between said rolls and between which said sheets are adapted to pass, complementary deforming dies on said carriers, and means to move said carriers in unison whereby a sheet may be deformed transversely while moving longitudinally and while being guided by said rolls.

15 3. In apparatus for forming metallic surfacing sheets the combination of upper and lower shafts 25 rotatable about spaced parallel axes and carrying complementary metal deforming dies extending parallel with said axes, means interconnecting said shafts whereby said shafts rotate in unison but in opposite directions, a fluid pressure operated motor to rotate said shafts, a valve controlling the flow of fluid under pressure to said motor, means adapted to be engaged by the leading ends of said sheets to initiate rotation of said shafts, means responsive to said initial rotation of said shafts to open said valve, and means to control the rate of flow of fluid to said motor when said valve is in open position.

20 4. In apparatus for forming metallic surfacing sheets the combination of upper and lower shafts positioned respectively above and below the path of travel of said sheets, complementary metal deforming dies fixed on said shafts, means interconnecting said shafts whereby the shafts rotate in unison but in opposite directions, means adapted 25 to be engaged by the leading ends of the sheets as the latter move along said path to initiate rotation of said shafts, a motor to rotate said shafts, and means responsive to the initial 30 rotational movement of said shafts to energize said motor.

45 5. Apparatus according to claim 3 further including means responsive to the advanced position attained by the sheets when between said shafts to interrupt the energization of said motor, and means to return said shafts to their initial 50 starting positions.

DWIGHT A. JOHNSTON.
